(57) **CLAIM**

The ornamental design for a "kit for hammock," as shown and described.

DESCRIPTION

FIG. 1 is a perspective view of the hammock showing my new design.

FIG. 2 is an exploded perspective view of FIG. 1, with the components shown separated for completeness of illustration.

FIG. 3 is a side elevation view of a first component of the kit for hammock shown removed from the kit for clarity of disclosure.

FIG. 4 is an end elevation view of the first component shown in FIG. 3.

FIG. 5 is a side elevation view of a second or third component of the kit for hammock shown removed from the kit for clarity of disclosure.

FIG. 6 is an end elevation view of the second or third component shown in FIG. 5.

FIG. 7 is an upper view of a fifth, sixth, ninth or tenth component of the kit for hammock of FIG. 1, shown removed from the kit for clarity of disclosure.

FIG. 8 is a side elevation view of the fifth, sixth, ninth or tenth component shown in FIG. 7.

FIG. 9 is a front view of a seventh or eighth component of the kit for hammock of FIG. 1, shown removed from the kit for clarity of disclosure.

FIG. 10 is a side elevation view of the seventh or eighth component shown in FIG. 9.

FIG. 11 is a front view of an eleventh component of the kit for hammock of FIG. 1, shown removed from the kit for clarity of disclosure.

FIG. 12 is a side elevation view of the eleventh component shown in FIG. 11.

FIG. 13 is an upper view of a twelfth, thirteenth, fourteenth, or fifteenth component of the kit for hammock of FIG. 1, shown removed from the kit for clarity of disclosure.

FIG. 14 is a side elevational view of the component shown in of FIG. 13.

FIG. 15 is an upper view of the fourth component of the kit for hammock of FIG. 1, through which the second, third, fifth, sixth, seventh, eighth, ninth, tenth and eleventh components are threaded, shown removed from the kit for clarity of disclosure.

FIG. 16 is an upper view of a sixteenth component of the kit for hammock, which is threaded through the fourth component, shown removed for clarity of disclosure; and,

FIG. 17 is a side elevational view of the sixteenth component shown in FIG. 16.
